(57) **CLAIM**

We claim the ornamental design for a 4-slice toaster, as shown and described.

DESCRIPTION

Cross-reference is made to co-pending U.S. Design patent application Ser. No. 29/369,600 entitled "2-Slice Toaster," which was filed on Sep. 10, 2010.

FIG. 1 is a front perspective view of the design of the 4-slice toaster;

FIG. 2 is a front elevation view of the 4-slice toaster of FIG. 1, with the rear elevation view being a mirror image of FIG. 2;

FIG. 3 is a first side elevation view of the 4-slice toaster of FIG. 1;

FIG. 4 is the second side elevation view of the 4-slice toaster of FIG. 1;

FIG. 5 is a top plan view of the 4-slice toaster of FIG. 1; and, FIG. 6 is the bottom plan view of the 4-slice toaster of FIG. 1. The portion shown in broken lines is for illustrative purposes only and forms no part of the claimed design.
